UNITED STATES PATENT OFFICE.

EUGENE A. WHITTEN, OF SANTA FE SPRINGS, CALIFORNIA, ASSIGNOR OF ONE-THIRD
TO ERNEST E. ANDERSON, OF BREA, CALIFORNIA, AND ONE-THIRD TO SHANNON
A. ERWIN, OF SANTA FE SPRINGS, CALIFORNIA.

OIL AND GAS SEPARATOR.

Application filed September 15, 1924. Serial No. 737,804.

To all whom it may concern:

Be it known that I, EUGENE A. WHITTEN, a citizen of the United States, residing at Santa Fe Springs, in the county of Los Angeles and State of California, have invented new and useful Improvements in Oil and Gas Separators, of which the following is a specification.

This invention is an oil and gas separator and consists of the novel features herein shown, described and claimed.

A leading object is to make an oil and gas separator having a float control oil outlet valve constructed and protected so that it cannot sand up and so that it will be self-cleaning, and the valve being constructed wholly inside of the separator so as to require no stuffing box, no outside lever, and no glands or packing.

Another object is to make an oil and gas separator having a weight controlled gas outlet and a float controlled oil outlet so that the gas pressure will assist in discharging the oil and keep the oil from overflowing into the gas container.

Other objects and advantages will appear from the drawings and specification.

The drawings illustrate the construction and operation of an oil and gas separator embodying the principles of the invention.

Figs. 1 and 1^A join together with Fig. 1^A fitting upon the bottom of Fig. 1, and make a sectional elevation of the oil and gas separator.

Fig. 2 is a fragmentary horizontal sectional detail on the line 2—2 of Fig. 1^A and looking downwardly as indicated by the arrows.

Fig. 3 is a cross section on the line 3—3 of Fig. 1 and looking downwardly as indicated by the arrows.

The details of the construction and operation shown in the drawings are as follows:

Where it is intended that the oil and gas separator is to be used in connection with an oil well having a large production, it is necessary that the separator be planned and built of considerable size, and the size and capacity is determined largely by the diameter and length of the main shell 1. A flange 2 extends outwardly around the lower end of the shell 1. A head 3 is secured

to the flange by bolts 4 and the drain or cleanout pipe 5 leads from the center of the head 3 and is controlled by a valve 6. The extreme lower part of the chamber 7 within the shell 1 above the head 3 is a settling basin for sand, mud, and the like, and during the operation of the separator 55 the valve 6 is to remain closed and is to be opened more or less from time to time to let the sand out of the chamber 7.

The valve casing 8 extends from the side of the shell 1 above the chamber 7 like the side outlet of a T. The casing 8 is of considerable size to form a chamber 9. A flange 10 is formed around the outer end of the casing 8. A head 11 is secured to the flange 10 by bolts 12. An oil outlet 70 pipe 13 is fixed through the head 11 and has a screw threaded nipple 14 extending into the chamber 9. The molasses valve fitting 15 is screwed upon the nipple 14 with its segmental finished face 16 extending inwardly. The shutter member 17 fits against the face 16. The shutter 17 has pintles 18 and 19 extending from its ends and levers 20 and 21 are placed in position with the pintles 18 and 19 extending through the levers and the levers are mounted upon pintles 22 and 23 extending from the sides of the valve fitting 15. The ends of the levers 20 and 21 are brought together inside of the shutter 17 and secured to a stop 24 by rivets 25, and extend inwardly and downwardly to form the arms 26. A link 27 is connected to the inner ends of the arms 26 by a pivot 28. A float 29 is connected to the link 27 and has guide ribs 30 75 engaging the inner face of the shell 1. The shell 1 is circular and the float 29 is circular and the ribs 30 space the float 29 from the shell 1 to allow the oil to run down around the float. As the float goes up the shutter 17 opens to allow the oil to run out through the pipe 13 and as the float comes down the shutter 17 closes to hold the oil and hold the gas in the shell 1. The float 29 operates in the chamber 21 extending upwardly from the chamber 7. A casing 32 is mounted at the top of the chamber 31, the casing 32 being considerably smaller than the shell 1, thereby forming a chamber 33 80 outside of the casing 32 and a chamber 34 85 inside of the casing. The lower end of the

85

105

casing 32 is connected to the shell 1 by a perforated flange 35.

The flow pipe 36 coming from the oil well is connected through the shell 1 to discharge the oil and gas into the chamber 33 and the oil is supposed to pass downwardly through the perforated flange 35 into the lower part of the shell 1, and in due course raise the float 29, open the shutter 17, and pass through the pipe 13 to a storage tank. The casing 32 forms a baffle plate extending up and down in the shell 1 for a considerable distance and if gas passes downwardly through the flange 35 with the oil, the gas may pass upwardly through the chamber 34. A gas separating chamber 37 is formed above the casing 32 in the shell 1. A flange 38 is formed at the upper end of the shell 1. A head 39 fits upon the flange 38 and has a valve seat 40 at its center. Supporting rods 41 are fixed through the head 39 around the valve seat 40 and extend downwardly into the upper end of the casing 32. Four porous diaphragms 42 and 43 are fixed upon the rods 41 and spaced apart and fit closely in the shell 1. After the head 39 carrying the rods 41 and diaphragms 42 and 43 have been placed in position in the chamber 37, the extension shell 44 having a flange 45 is applied and bolts 46 are inserted through the flange 45 through the head 39 and through the flange 38 to make an air tight joint. The gas pipe 47 extends from the side of the extension shell 44 to be connected to any suitable means for disposing of the gas such as a container or pipe line. A flange 48 is formed at the upper end of the extension shell 44. A head 49 fits upon the flange and bolts 50 connect the head to the flange. A valve 51 fits the valve seat 40. A valve stem 52 extends from the valve 51 through a stuffing box construction 53 upon the head 49. A bearing post 54 extends upwardly from the head 49. A lever 55 is connected to the bearing post 54 and to the upper end of the stem 52. A rod 56 is connected to the opposite end of the lever 55 from the post 54 and carries a base 57 and an assortment of weights 58 applied to the rod and resting upon the base. The pressure at which the valve 51 will open may be accurately regulated by manipulating the weights 58 as in operating a scale. A regulating valve 59 controls the flow of oil from the well to the pipe 36 to the separator and the chambers 7, 31, 33, 34 and 37 will fill with oil and gas and the valve 51 will hold the gas pressure to the desired extent and the oil will raise the float 29 to open the shutter 17 and the gas pressure will assist in forcing the oil to flow through the pipe 13 to the tank or pipe line. When the gas flows upwardly through the porous diaphragms 42 and

43, the particles of oil will be broken up and separated from the gas and the oil will flow downwardly and the gas will flow upwardly and as the pressure goes over the predetermined point the valve 51 will open 70 and the gas flow through the pipe 47. The continually rising gas pressure will increase the speed of the flow of oil through the pipe 13 as required to keep the oil from overflowing upwardly to the gas pipe 47. 75

The oil outlet valve in the casing 8 is in a side pocket entirely inside of the casing, and there is no stuffing box or outside lever and nothing to get out of order, and it is above and at one side of the settling basin 80 7 and out of the line of the sand flowing downwardly from the inlet pipe 36. If proper attention is given to the matter of draining the sand out of the chamber 7 by manipulating the valve 6, there is no reason that the separator should ever clog. 85

It will be readily understood that oil entering the shell 1 through the inlet pipe 36 upon flowing downwardly in the shell 1 will tend to have the majority of the sand 90 therein settle out and fall into the chamber 7 from which it may be readily removed. By disposing the valve casing 8 above the bottom of the shell and upon one side thereof, there will be very little tendency for 95 any of the sand to pass out through the discharge pipe 13. By providing the discharge pipe 13 with a valve fitting 15 having a convex seating surface over which the shutter 17 is slid able, the sand which may enter the valve casing 8 will be somewhat directed away from the entrance to the discharge pipe 13, and there will be very little wear. Any sand which may settle upon the convex seating surface 16 will be removed 100 therefrom by the shutter 17 so that the sand which does enter the valve casing 8 will not have a chance to quickly wear out or loosen the float controlled valve. 105

Various changes may be made without departing from the spirit of the invention as claimed:

I claim:

1. An oil and gas separator comprising a shell, an annular foraminated diaphragm mounted in the shell, a casing mounted on the diaphragm and extending upwardly and forming an annular chamber above the diaphragm, the chamber of the shell below the diaphragm being an oil chamber, a valve casing near the lower end of the shell, a float in the shell, an oil outlet pipe extending through the outer end of the valve casing, a valve having a curved face upon the inner end of the outlet pipe in the valve casing, a curved shutter member slid able on the curved face, levers pivoted to the oil outlet pipe and having a pivotal connection to the shutter and a link connected to the levers and to the float and adapted to operate the 110 115 120 125 130

shutter, an oil drain having a valve at the bottom of the shell and an oil inlet to the annular chamber.

2. An oil and gas separator comprising in combination a shell, an annular foraminated diaphragm, a casing mounted on the diaphragm and extending upwardly forming an annular chamber with the shell, the chamber below the diaphragm being an oil chamber, a float in the oil chamber, an oil outlet having a valve situated above the base of the shell and operated by the float, an oil drain having a valve at the bottom of the shell, an oil inlet to the annular passage, and a gas outlet operated by the gas pressure at the top of the shell.

3. An oil and gas separator comprising in combination a vertical cylindrical shell, an annular foraminated diaphragm forming

an oil chamber therebelow, a casing extending upward from the diaphragm and forming an annular chamber with the shell and an open passage through the center, foraminous diaphragms above the casing forming a gas separating chamber, a head across the upper end of the separating chamber having a weighted valve seated therein, a gas outlet above the head, an oil inlet through the shell above the annular diaphragm, a float slidably mounted in the oil chamber, a valve 30 casing opening through the shell into the oil chamber, an oil outlet valve therein operated by the float, and an oil drain having a valve at the bottom of the shell.

In testimony whereof I have signed my 35 name to this specification.

E. A. WHITTEN.
